THERMAL CONTROL ADJUSTER

James L. Breese, Santa Fe, N. Mex., assignor to
Oil Devices, Santa Fe, N. Mex., a limited partnership of Illinois

Application February 3, 1941, Serial No. 377,143

7 Claims. (Cl. 236—99)

My invention relates to an improvement in control valves and has for one purpose the provision of a thermally controlled valve applicable for use with liquid fuel lines.

Another purpose is the provision of a control valve in which the flow of oil may be caused to vary in response to temperature conditions.

Another purpose is the provision of such a valve in which the response of a valve to temperature changes may be adjusted or controlled.

Another purpose is the provision of means for interrupting or cutting out the thermal control.

Other objects will appear from time to time throughout the specification and claims.

I illustrate my invention more or less diagrammatically in the accompanying drawing, wherein—

Figure 1 is a vertical longitudinal section through a float valve and chamber;

Figure 2 is a plan view of the structure shown in Figure 1.

Like parts are indicated by like characters throughout the specification and drawing.

Referring to the drawing, 1 indicates any suitable float chamber having a removable cover plate 2. 3 is a fuel line adapted to deliver a liquid fuel to the chamber 1 from any suitable fuel source not herein shown. It communicates with the fuel inlet passage 4 having a bore 5 and a valve seat 6. 7 is a sleeve extending upwardly above the inlet passage 4 and having a somewhat larger bore 8. 9 are liquid flow passages above the valve seat formed in the sleeve 7. 10 is a bracket upwardly and outwardly extending from the sleeve 7. Mounted thereon as at 11, is a valve control lever 12 secured at the outer end of which is a suitable float 13. Axially movable within the bore is a valve stem 14 which is loosely fitted to the lever 12 as at 15. It may include, for example, a conic valve portion 16 adapted to engage the valve seat 6. It will be understood that when the level of liquid fuel within the chamber 1, reaches a predetermined height, the float 13 rises and moves the valve 16 into closed position, thus cutting off any further supply of fuel to the chamber 1.

20 is a liquid fuel outlet line extending, for example, to any suitable burner or other fuel consuming mechanism not herein shown. 21 is a fuel outlet passage member extending upwardly within the chamber 1, and having any suitable valve seat 22. 23 is any suitable valve stem having a bottom portion 24 which may conform to the valve seat 22 and may have any suitable metering slots 25 in the lower portion 26 of the

valve. The valve stem 23 has an upward prolongation 27 of smaller diameter which may be guided in any suitable way and may, for example, extend outwardly and upwardly through a hole in the cover 2 of the chamber, the outwardly extending portion being indicated as at 28. Any suitable spring 29 tends normally to raise the valve stem and thus move the valve to open position. The spring 29 for example, may be compressed between the top of the sleeve 21 and any suitable abutment 30 on the valve stem 23.

Pivoted on the bracket 10 as at 31 is a bell crank lever having a generally vertical arm 32 and a generally horizontal arm 33. The horizontal arm 33 may be apertured as at 34 to permit the valve stem extension to pass therethrough and the arm 33 abuts against any suitable shoulder 35 of the valve stem. 36 is any suitable heat responsive member herein shown as a bellows with a communicating passage 37 to any suitable bulb not here shown. It will be understood that in response to heat conditions, at the burner or elsewhere, the bellows may expand as the temperature rises and may contract as the temperature drops. The bellows is formed with a member 38 carrying any suitable pin or stem 39 which may engage a depression 40 in the bell crank lever arm 32. It will be observed that as the bellows 36 expands, it exerts pressure against the lever 32 which tends to depress the other bell crank lever arm 33 and thus to close the valve stem 33 against the compression of the spring 29, thus cutting down the flow of fuel along the line 20. The effect of heat on the expansion of the bellows 36 may be varied, however, by means susceptible of manual adjustment. I illustrate, for example, a control knob 41, having a stem 42, screw threaded in any suitable bearing 43 mounted on or formed in the cover 2. The lower end of the stem 42 engages the bell crank lever arm 44 of a lever pivoted as at 45 in relation to the float chamber. A lower or depending bell crank lever 46 is opposed to the bell crank lever arm 32 and between them is compressed a spring 47 which tends to resist the expansion of the bellows 36. The compression of the spring 47 may be adjusted by rotation of the manual knob 41 as its rotation causes the stem 42 to rise or fall in relation to the cover 2. I may, limit this rotation, for example, by any suitable pins or stop members 50, 51, in conjunction with a projection 52 on the knob 41. I may permit any suitable range of rotation of the knob 41 but I have indicated a rotation of about 180 degrees.

It will be understood that the cover may be provided with any suitable calibration so that the user may set the knob at high, medium, low or off or any desired intermediate settings. It will be understood, for example, that more than the four positions herein shown in Figure 2 may be calibrated. In order to cut out or "short circuit" the thermal control, I provide means associated with or operated by the knob 41 for positively moving the valve stem 23 to the minimum flow or off position. I illustrate, for example, a cam 53 located below and rotating with the knob 41. Any suitable cam may be employed but I find it advantageous to employ a spring cam. This cam, when the knob 41 is moved to the off position, overrides the upward extension 28 of the valve stem 23 and positively closes the valve against the compression of the spring 29 and entirely cuts out the operation of the above described bellows. In other words, when the knob 41 is moved counterclockwise to 180 degrees, referring to the position of the parts in Figure 2, the cam 53 is effective positively to move the valve to a minimum setting and no changes in temperature or changes in expansion or contraction of the bellows 36 will have any effect on the setting of the valve stem 23. At all other times, however, the bellows may effectively control the valve by shutting it off in response to expansion of the bellows by heating of the bulb in communication with the passage 37. The response of the bellows to temperature conditions is in such case controlled or varied by the compression of the spring 47, which in turn is controlled by the manual setting of the knob 41.

It will be understood that, whereas I have shown a very simple form of control, with the direct connection between the adjusting knob and the valve stem, in more complicated forms of control it may be necessary to employ intermediate levers, linkages, or the like.

It will be realized that my description and drawing are in a broad sense illustrative or diagrammatic and that I do not wish to be limited to the specific showing herein. Many changes may be made in the size, shape, number, proportion and disposition of parts without departing from the spirit of my invention. I may, for example, have any suitable intermediate actuating connection between the knob 41 and the stem 23 and the employment of a bellows is merely an illustration of a practical heat responsive element.

The use and operation of my device are as follows:

In controlling the flow of liquid fuel, for example, to a pot type burner, although my control may be used with other types of burner, I find it advantageous to provide both a mechanical shut off and a thermally responsive control. Assume that the operator of the burner wishes to turn it off altogether or to set it at a pilot minimum, he need only so actuate the knob 41 or its equivalent that the valve stem 23 is positively closed. If the parts are proportioned for a complete shut off, then no fuel at all will flow. If an oil pilot is employed with the burner, the valve 23 may be so proportioned and set as to permit the passage of a minimum flow of fuel sufficient to maintain pilot combustion when the valve stem is moved into its minimum flow position. Assume, however, that the operator wishes to have the flow of fuel respond to heat conditions at the burner or elsewhere, he then moves the control knob 41 in such position as to place the cam 53 out of line

with the valve stem extension 28. The flow through the line 20 is then basically governed by the expansion and contraction of the bellows 36 or its equivalent. For example, in the form herein shown, an increase in heat causes an expansion of the fluid within the bellows 36 and thereby causes a thrust of the pin 39 against the lever arm 32 which is effective to move the lever arm 33 downwardly and thus depress the valve 23. This reduces or cuts off the flow of fuel depending upon the degree of expansion of the bellows 36, and causing the controlling temperature to drop. This in turn causes a contraction of the bellows 36 and permits the arm 33 to rise and spring 29 to move the valve stem 23 to a more open position. The user can control or adjust the response of the valve stem 23 to the expansion or contraction of the bellows 36 by varying the spring loading provided by the coil spring 41 under compression between the lever arms 32 and 46. This variation or control of the spring loading is obtained by rotating the knob 41 in the particular embodiment of the invention herein described and shown. If the knob 41 is so rotated as to cause the screw threaded stem 42 to descend, then the loading the spring 47 is increased and the expansion of the bellows 36 is resisted. Therefore, greater heat is required to expand the bellows 36 sufficiently to move the valve 23 to the closed or pilot position.

I claim:

1. In a valve structure for controlling the flow of liquid fuels, a fuel chamber and means for maintaining a supply of liquid fuel therein, a fuel outflow line in communication therewith, a valve seat therefor, a movable valve member adapted to move toward and away from said seat, a heat responsive element and means for varying the setting of said valve in response to actuation of said heat responsive element, and means for varying the movement of said heat responsive element and thus for varying its effect upon the seating of said valve in response to temperature changes, including spring loading means aligned with and opposed to said heat responsive element and means for varying the loading of said spring loading means including an exterior manually movable control element and a connection between said control element and said spring loading means, and an additional connection between said manually operable control element and said valve means independent of and in parallel with the spring loading means and the connection between the control element and the spring loading means adapted at one position of said manually operable control element to move said valve means independently of the operation of said heat responsive element.

2. In a valve structure for controlling the flow of liquid fuels and the like, a fuel chamber and means for maintaining a supply of liquid fuel therein, a fuel outflow passage in communication therewith and a fuel valve adapted to control flow through the passage, a lever adapted to control the position of the valve, a heat responsive element adapted to rotate the lever, spring means aligned in opposition to the heat responsive element adapted to resist movement of the valve in the closing direction and manually controlled means adapted to vary the effect of the spring, said manually controlled means being movable to vary the effect of the spring throughout a predetermined range and positive means controlled by the manually controlled means and effective

toward the lower extremity of the range of movement thereof for positively closing the valve.

3. A control for oil burners and the like comprising a float chamber, spaced fuel inlet and outlet passages, a bracket associated with the fuel inlet, a lever pivoted on the bracket, a float at one end, and a fuel inlet control valve at the other end of the lever, a metering valve for the fuel outlet, yielding means tending to urge the metering valve toward the open position, a heat responsive element in the housing, a valve actuating bell crank lever pivoted on the float lever bracket, having a generally horizontal arm loosely engaging the metering valve, a shorter generally vertical arm and a connection between it and the heat responsive element, a second bell crank lever pivoted in the housing, having a short generally vertical arm in opposition to the vertical arm of the valve actuating lever, a loading spring interposed between the two short arms, a screw, threaded in the housing, a manual control button supported thereon outside of the housing, the inside end of the screw engaging the longer arm of the second lever, the metering valve having a stem projecting upwardly through the wall of the housing adjacent the control button, a cam carried by the screw adapted to engage the stem of the metering valve to force it to closed position independent of the valve actuating lever.

4. A control means for oil burners and the like comprising a float chamber, spaced fuel inlet and outlet passages, a bracket associated with the fuel inlet, a lever pivoted on the bracket, a float at one end, and a fuel inlet control valve at the other end of the lever, a metering valve for the fuel outlet, yielding means tending to urge the metering valve toward the open position, a heat responsive element in the housing, a valve actuating bell crank lever pivoted on the float lever bracket, having a generally horizontal arm loosely engaging the metering valve, a shorter generally vertical arm and a connection between it and the heat responsive element, a second bell crank lever pivoted in the housing, having a short generally vertical arm in opposition to the vertical arm of the valve actuating lever, a loading spring interposed between the two short arms, a screw, threaded in the housing, a manual control button supported thereon outside of the housing, the inside end of the screw engaging the longer arm of the second lever, the metering valve having a stem projecting upwardly through the wall of the housing adjacent the control button, a cam carried by the screw adapted to engage the stem of the metering valve to force it to closed position independent of the valve actuating lever, the cam being so positioned so as to engage the stem of the valve only at one end of the rotary excursion of the control button.

5. A control means for oil burners and the like comprising a float chamber, spaced fuel inlet and outlet passages, a bracket associated with the fuel inlet, a lever pivoted on the bracket, a float at one end, and a fuel inlet control valve at the other end of the lever, a metering valve for the fuel outlet, a heat responsive element in the housing,

a valve actuating bell crank lever pivoted on the float lever bracket, having a generally horizontal arm loosely engaging the metering valve, a shorter generally vertical arm and a connection between it and the heat responsive element, a second bell crank lever pivoted in the housing, having a short generally vertical arm in opposition to the vertical arm of the valve actuating lever, a loading spring interposed between the two short arms, a screw, threaded in the housing, a manual control button supported thereon outside of the housing, the inside end of the screw engaging the longer arm of the second lever, the metering valve having a stem projecting upwardly through the wall of the housing adjacent the control button, a cam carried by the screw adapted to engage the stem of the metering valve to force it to closed position independent of the valve actuating lever.

6. Means for controlling the flow of liquid fuels and the like including a housing container, a fuel chamber, means for maintaining a supply of liquid fuel therein, a fuel supply passage leading therefrom and a fuel valve controlling the passage, the valve having a stem projecting beyond the housing, a valve actuating bell crank lever within the housing engaging the valve at one end, a heat responsive element enclosed within the housing engaging the other end of the bell crank lever, a second bell crank lever pivoted within the housing, a spring adapted to be compressed between the one end of the valve actuating lever and the second lever, an adjusting screw, threaded in the wall of the housing adapted to engage the free end of the second lever, a manual control member on the free end of the screw where it projects beyond the housing, and a connection between said manual control member and the outer end of said outwardly projecting valve stem adapted, in response to a predetermined movement of said manual control member, positively to urge said valve stem toward valve closing position.

7. Means for controlling the flow of liquid fuels and the like including a housing container, a fuel chamber, means for maintaining a supply of liquid fuel therein, a fuel supply passage leading therefrom and a fuel valve controlling the passage, the valve having a stem projecting beyond the housing, a valve actuating bell crank lever within the housing engaging the valve at one end, a heat responsive element enclosed within the housing engaging the other end of the bell crank lever, a second bell crank lever pivoted within the housing, a spring adapted to be compressed between the one end of the valve actuating lever and the second lever, an adjusting screw, threaded in the wall of the housing adapted to engage the free end of the second lever, a hand wheel on the free end of the screw where it projects beyond the housing, a cam carried by the hand wheel adapted to engage the end of the valve stem at one end of the excursion of the hand wheel to positively force the valve into closed position.

JAMES L. BRESEE.
